(57) **CLAIM**

The ornamental design for an arm pad accessory, as shown and described.

DESCRIPTION

FIG. 1 is a front prospective view of an arm pad accessory for use when feeding an infant embodying my design.

FIG. 2 is a left side elevational view thereof.

FIG. 3 is a right side elevational view thereof.

FIG. 4 is a top plan view thereof.

FIG. 5 is a bottom plan view thereof.

FIG. 6 is a front elevational view thereof.

FIG. 7 is a rear elevational view thereof.

FIG. 8 is a perspective view thereof, showing the arm pad accessory in use.

FIG. 9 is a top perspective view thereof, showing the arm pad accessory unfolded; and,

FIG. 10 is a bottom perspective view of the arm pad accessory shown in FIG. 9.

The broken lines showing an infant and arm in FIG. 8 forms no part of the claimed design. All other broken lines represent stitching.
